COMBINED PESTLE AND MERCURY
DISPENSING APPARATUS

Frederick F. Marschalk, Augusta, Ga.

Application November 19, 1945, Serial No. 629,364

3 Claims. (Cl. 241—38)

1
This invention relates to a combined pestle and dispensing means therefor.

Heretofore it has been common practice to provide amalgam dental fillings by placing a suitable amount of alloy in a mortar and then add a quantity of mercury to the mortar for amalgamation with the alloy in which the amalgamating process was accelerated by the use of a pestle in triturating and mixing the materials.

I have found that I can proceed more expeditiously and accurately by providing a reservoir for mercury within the handle of the pestle.

It is an object of my invention to provide a reservoir in the handle of a pestle including a valve controlled dispensing and measuring means to feed a quantity of mercury down over the side of the pestle body into the mortar and upon the alloy or metallic mix within the mortar.

It is an object of my invention to provide a pestle handle with a removable cap comprising a flanged ring in combination with a stretchable diaphragm which together may serve as a base for the apparatus whereby the apparatus may be stood in an inverted upright position on a substantially horizontal support when not in use.

It is an object of this invention to provide an elastic flexible diaphragm attachably and detachably secured on the end of the pestle handle by a flanged ring.

It is an object of this invention to provide an attachable and detachable pestle body for the handle whereby an old worn-out pestle body may be replaced by a new one.

It is an object of this invention to provide a valve body that is spring actuated to closed position by a spring and manually actuated to an open position by finger pressure on a resilient flexible diaphragm.

It is an object of my invention to provide a receiving compartment for receiving the mercury from the valve controlled reservoir and to guide and conduct the charge of mercury gravitationally down and over an inclined portion of the pestle body through an exit located at the bottom of the inclined portion whereby the charge of mercury is deposited in the mortar.

It is also an object of this invention to make the pestle handle of substantially transparent plastic material whereby the contents of the reservoir may be noted from time to time.

Other objects and advantages will be revealed in connection with the detailed description of the accompanying drawings which form a part of the specification and in which:

Fig. 1 is a sectional view of my new dispensing

2
pestle, taken centrally and longitudinally thereof and showing the control valve closed.

Fig. 2 is similar to Fig. 1 except that the control valve is in a depressed position after the release of a charge of mercury, and

Fig. 3 is similar to Fig. 1 except that mercury is being dispensed without being measured.

The drawings are merely illustrative and not definitive of my invention except as defined by the subject matter claimed herein.

The reference characters identify the parts disclosed in both the drawings and specifications.

In the drawing the pestle 1 consists of a hollow substantially transparent handle 2 constituting a reservoir 3 containing mercury 4.

Since the contents of the reservoir 3 is to be visibly observed it will be sufficient to use translucent material if so desired.

The plastic handle may be made of molded phenolic plastics, methyl methacrylate plastics, vinyl resin plastics, polystyrene plastics, acrylic resins, cellulose acetate, ethyl cellulose, etc.

The handle 2 is provided with a combined valve seat and valve stem guide 5. The handle 2 is provided with an extension 6 beyond the valve seat and receives one end of a pestle body 7 which is detachably secured therein by any suitable soluble glue 8. The pestle body 7 is provided with an inclined end 9 located within the extension 6. The extension 6 is provided with an exit orifice 10 located at the lowest portion of the inclined end 9.

The tubular extension 6 of the handle forms a connection with the pestle 7, said connection constitutes a joint and the exit orifice 10 is located in the connection or joint. The exit orifice 10 opens on the outside of the pestle and conducts or guides the mercury over the outside surface portion of the pestle 7.

A valve stem 11 is provided with a valve head 12 cooperating with the valve seat and guide 5. The valve stem 11 is also provided with a reduced portion 13 connecting the valve head with the remainder of the valve stem 11. This reduced portion 13 forms a passageway from the reservoir 3 to the compartment 14. The upper end of the valve stem 11 is provided with a removable knob preferably screw threaded to the end of the stem 11 and located substantially flush with the upper end of the reservoir 3.

50 A flexible elastic, stretchable diaphragm 16 extends over the top of the tubular reservoir in engagement with the knob 15 and is secured to the reservoir 3 by a screw threaded flanged ring 17. The valve stem 11 is surrounded by a helical compression spring 18 preferably made of carbon steel

or any suitable material that will not amalgamate with the mercury.

The valve stem 11 and the valve head 12 and the knob 15 may be made of substantially pure iron or any suitable material such as plastic material that will not amalgamate with the mercury.

If the valve stem 11, the knob 15 and valve head 12 are made from a suitable plastic material, such as specified for making the hollow handle, then the plastic material for said valve stem etc. need not be made of transparent or translucent material.

The pestle body 7 may be made of porcelain or any suitable plastic material. The exit orifice 10 is formed in the connection or joint of the tubular extension 6 with the pestle 7. The exit orifice 10 leads from a position above and at the lowermost portion of the incline or ramp 9 to the outer surface portion of the pestle 7, so that the mercury can roll down or descend on the pestle into the mortar 19 without excessive splashing.

The mortar 19 is conventional and forms no part of my invention but is disclosed merely to visualize clearly the use and operation of my combined pestle and dispensing device or apparatus.

When the manufactured parts are ready for assembly the valve stem 11 is inserted through the valve seat and guide 5 and the spring 18 is placed in position surrounding the stem 11.

The spring 18 is depressed so that the knob 15 may be applied to the valve stem 11 to maintain the spring under tension. Now the stretchable diaphragm 16, which is preferably made of rubber, is placed over the end of the tubular hollow handle and secured in position thereon by the screw threaded flanged ring 17. The pestle body 7 is detachably secured in place by a soluble cement or glue so that an old worn-out pestle body may be removed by dissolving the glue in water or other appropriate solvent.

In operation the apparatus comprising the pestle is used in the ordinary way in connection with a mortar containing the dental filling alloy or mix. When it is desired to dispense a charge of mercury the valve is depressed by a finger tip of the operator as indicated in Fig. 2. If the release of a charge of mercury is not sufficient to make the amalgam of proper consistency a further charge may be added by repeating the operation of depressing the valve against the tension of the spring. If more than a measured charge is desired the pestle may be operated as indicated in Fig. 3. If it is desired to empty the reservoir 3 the valve may be maintained in an open position as clearly indicated in Fig. 3.

In Fig. 2 it is to be noted that the valve stem 11 exactly fits the valve seat outlet and cuts off the exit of mercury 4 from the reservoir 3 so that the stem 11 serves as a sliding cut-off valve whereas the valve head 12 operates as or similar to a poppet valve of an internal combustion engine.

It is also to be noted that the inclined end 9 of the pestle body 7 serves as a stop to prevent excessive range of movement of the diaphragm 16 as shown in Fig. 2.

When it is desired to place the pestle in an out of use position it may be inverted and supported in that position on a substantially horizontal support thereby using the ring 17 as a base.

While I have described my pestle as being particularly useful in connection with the dispensing of mercury over a pestle body it appears to be self-

evident that it could be used for dispensing other liquids as well as powdered material.

Having fully disclosed my said invention what I claim is:

1. In a combined pestle and mercury dispensing means therefor, comprising a tubular transparent handle defining a mercury containing reservoir, said handle having a tubular extension receiving one end of said pestle, said pestle being glued in said tubular extension defining a joint, said joint having an exit orifice therein opening on the surface portion of said pestle, said handle having therein a valve stem and a valve head said head being connected to the valve stem by a reduced portion of said stem in combination with a combined valve stem guide and valve seat portion, spring means on said stem to actuate said valve head to closed position against said valve seat portion in further combination with a stretchable diaphragm secured over the end of said tubular handle by a screw threaded flanged ring, a knob disposed on the end of the valve stem and in contact with said diaphragm whereby said valve stem and valve head may be operated to release a charge of mercury from said reservoir on to the surface portion of said pestle.

2. In a combined pestle and mercury dispensing means therefor, comprising a tubular plastic substantially transparent handle said handle defining a mercury containing reservoir, said reservoir having adjacent one of its ends a transverse portion defining a combined dispensing opening, a valve stem guide and a valve seat, the upper end of said tubular handle being closed by a stretchable diaphragm, said diaphragm being secured in position by a screw threaded flanged ring, in combination with a valve stem having a valve head on one of its ends and a detachable knob on its other end, said knob being in contact with the diaphragm whereby said valve stem and valve head may be operated by finger pressure on said diaphragm said pestle having a flat inclined upper end portion, said handle having on its lower end a tubular extension receiving said upper end portion of said pestle, including its inclined portion, in further combination with an exit orifice located above but at the bottom of said inclined portion and between said extension and pestle whereby said mercury may be conducted down over the outer surface of the pestle into the mortar without excessive splashing or spattering of the mercury.

3. In a combined pestle and dispensing means therefor, comprising a tubular plastic transparent handle said handle defining a reservoir for mercury, said handle having a transverse portion located intermediate the ends thereof, said transverse portion defining a combined dispensing opening, a valve stem guide and a valve seat, a valve stem having a valve head co-operating with said valve seat, said valve stem extending through said dispensing opening and valve stem guide, said valve and valve stem being provided with operating means, in combination with a tubular extension on said handle located below said transverse portion and receiving the upper end of a pestle body, said pestle body having a flat inclined upper portion to form a guide for the dispensed mercury, said extension having an exit orifice the major portion of said orifice being located between itself and the lowest position of said inclined portion, and leading from a position above but at the lower most portion of said inclined portion whereby mercury may be dispensed over an outside surface portion of the pestle body, said

pestle body being detachably secured in said extension by a soluble glue.

FREDERICK F. MARSCHALK.
